UNITED STATES PATENT OFFICE.

JAMES MARK McGINNIS BARR, OF LONDON, ENGLAND.

CALCULATING MACHINE.

Application filed July 9, 1923. Serial No. 850,501.

To all whom it may concern:

Be it known that I, JAMES MARK McGINNIS BARR, a citizen of the United States of America, and residing in London, S. W. 1, 5 England, have invented certain new and useful Improvements in Calculating Machines, of which the following is a specification.

This invention relates to calculating machines of the kind in which the partial products resulting from any multiplication within the limits of the machine are stored within the machine and are co-ordinated or selected to be delivered to suitable counting means by which they are added together to give the result, such partial products being represented by balls or other separate objects.

The present invention has for its object to 20 simplify and cheapen the construction of calculating machines of the above kind and the invention consists in a calculating machine of the kind referred to comprising a plurality of counting mechanisms, corresponding to the various denominations occurring in the maximum result obtainable in the machine, each of which is associated with means whereby the counter may have delivered to it for counting any of the partial products corresponding to its denomination that may occur in any calculation within the limits of the machine.

The invention also consists in a calculating machine of the kind referred to in 35 which each counter with its associated means for storing and delivering the partial products to be delivered thereto is formed as a self-contained unit.

The invention further consists in a calculating machine of the kind referred to in 40 which the means co-ordinating any particular partial product required also actuates the means by which the balls or other separate objects representing such partial products are freed for delivery to the particular counting mechanism concerned.

In machines of the kind in question it has been found necessary hitherto to store separately the individual partial products for 45 each co-ordination that may be necessary within the limits of the machine even where the partial products may be of the same value. For example, a co-ordinating of 6 and 4 gives the partial 24 which is also produced when the numerals 8 and 3 are co-ordinated, and in such cases it has hitherto

been necessary to store two separate partials to be found by each of such co-ordinations.

The present invention, however, consists in a calculating machine of the kind referred to in which the means for co-ordinating the partial products are such that this disadvantage is completely obviated.

The invention further consists in other details and arrangements hereinafter described or indicated.

In the accompanying drawing, Fig. 1 illustrates diagrammatically one convenient form of counting mechanism with its associated co-ordinator in accordance with the 70 invention. Fig. 2 is a detail in side elevation of a modification of the invention; Fig. 3 is a front view of Fig. 2; Fig. 4 is an elevation of the side opposite that shown in Fig. 2, partly in section; Fig. 5 is a diagrammatic view similar to Fig. 1 showing means for operating the item rods and rate strips, and, Fig. 6 is a detail section of Fig. 5. Fig. 7 is an enlarged fragmentary perspective showing in detail the device for 80 permitting movement of the stops or shelves.

In carrying my invention into effect in one convenient manner as, for example, in its application to a calculating machine 85 adapted to deal with the decimal system, I provide a plurality of counting mechanisms equal in number to the number of digits occurring in the maximum result obtainable within the limits of the machine and such 90 counting mechanisms correspond in the usual manner with the respective denominations occurring in such result; that is to say, there is a counter for the units, a counter for the tens, a counter for the hundreds and 95 so on and there may also be counters for the integers occurring after the decimal point. Each of such counting mechanisms comprises a rotary toothed wheel *a* or other member adapted to be rotated step by step 100 by the passage of successive balls *b* through the counter, there being ten of such steps in the decimal machine and corresponding respectively with the points 1, 2, 3, 4, 5, 6, 7, 8, 9, 0, which may be indicated on a dial 105 or other indicator associated with the counter.

In connection with each counter and positioned so that the balls located therein are in a position to operate the counter I provide a tube *c* in the form of a vertical or other suitably disposed loop, which loop is

closed on itself except at that point where the member *d* for passing the balls through the counter is associated with the tube, which member itself substantially closes the loop.

The storage and delivery tube for the balls or other objects is of such a length that the tube is capable of delivering to its counter balls representing the greatest 10 partial product which can occur within the limits of the machine (this being in the example chosen 81 which is the partial product produced by the co-ordination of 9 with 9) and there must also be an added 15 length in each limb of the loop so that when, for example, the largest number of balls is delivered at one count and on the down side of the loop there will be sufficient room in the limb above such balls to accommodate 20 an equal number of balls which will be displaced from the other limb by the balls passing through the counter. Each section (that is, each counter with its associated ball storing and delivering mechanism) is 25 provided with a rotating disc *d* which is associated with a pivoted and spring-controlled wedge or shoe member *e* or the like so disposed in relation to the rotating disc that the two together constitute virtually a 30 friction drive by which the balls are driven successively through the counter. The shoe member is provided with an extension *f* which acts as a pawl which projects somewhat into the up or nondelivery side of the 35 tube in order to prevent overrunning or jumping of the balls or their return by their own weight against the counter. As the shoe member is operated in succession by each ball as it passes through the counter 40 the pawl will be momentarily withdrawn from the up side of the tube to permit of the passage of a ball from the lower to the upper side of the projecting pawl member as a corresponding ball passes through the 45 counter.

In the delivery side of the tube and just above the counter there is a lower shelf or stop *g* which projects within the tube and is adapted to retain the balls in position above it, and in order to be able to select any desired number of balls for delivery to the counter corresponding with any particular partial product determined by the co-ordination 50 of two members (such, for example, as an "item" which means, say, quantity of goods, or stands for the first multiplier and a "rate" which means, say, price or in general stands for the second multiplier) I provide in conjunction with the delivery part of each tube or section a series of shelves *h*, stops or like members, any one of which may be made to project into the tube and so cut off a number of balls equal to the value of the particular partial product corresponding with such shelf. Suppose, for

example, that the item 6 is co-ordinated with the rate 4, the shelf to be operated would be 24 balls above the lower stop so that when the latter is released the 24 balls would be delivered to the counter which would thus 70 show 4 at the end of the count, and having made two complete revolutions would have two carries for delivery to the counter of next higher denomination. By my invention also the same shelf would be operated 75 if the item 8 were co-ordinated with the rate 3 or if the items 4 and 3 were respectively co-ordinated with rates 6 and 8, so that in this way I reduce the number of partials required for the co-ordination of any of the 80 first nine digits with any other to 36.

For the purpose of operating the "carries" each section may comprise two tubes *c' c²* (Figure 3) similar to the tube *c* above referred to and arranged side by side, the 85 tube *c'* in each case being for the ordinary integers as above described while each tube *c²* serves as the carry tube for the carries from the next lower denomination.

Each pair of tubes is mounted with a 90 counter *a* common to the two tubes so that a ball passing down either tube will operate said counter. Each tube *c²* is provided with a single ball release device which may, for example, comprise a pivoted bell crank 95 lever, one arm *n* of which is furnished with two stops *n'* situated apart from one another by a distance equal to the diameter of one ball while the other arm *n²* forms an armature adapted to be attracted by an electro- 100 magnet *o* when the latter is suitably energized.

Each electromagnet may be connected with the arm or switch *p* of the counter of next lower denomination and with a contact 105 *p'* situated between the 9 and 0 points of the counter, the arrangement being such that as the arm *p* contacts with the contact *p'* the electromagnet is energized so that the stops *n'* are brought into such a position 110 that the ball held between them will be allowed to drop into the tube *c²* and as soon as the contact of *p'* is broken the ball releasing arm returns to its normal position (either by its own weight or by a spring), the ball 115 released from the arm being replaced by another ball before the arm is normally positioned as shown in Figure 4.

It will be obvious that if the carry balls delivered to the tube *c²* were allowed to pass 120 through the counter as they are delivered it might be that an ordinary integer ball from the tube *c'* may be passing through the counter at the same time so that the carry would then be lost and in order to avoid this 125 I arrange a stop *r* (similar to the stop *g* above described) at the bottom of each carry tube *c²* upon which all the carry balls released will rest until after the integer count, a special "finish" key may then be pressed.

or the return motion of the last key to be pressed home may (through a fan or suitable delay) be utilized to remove the stops r and so allow of the carry balls to register on the counters.

In order to select particular partial products required for any specific calculation I provide co-ordinating means whereby the items and rates may be co-ordinated and I arrange that the co-ordinating devices shall actuate the shelves or stops h by which the partial products co-ordinated are freed for delivery to their respective counters.

In the construction illustrated I arrange a framework consisting of 9 vertical rods i which I denote "item rods" and which correspond with the various integers from 1 to 9 that may occur in the item. Such rods are associated with inclined strips k , bars or the like of suitable material which are also 9 in number and which I term "rate strips" since they correspond with the integers occurring in the rate.

The strips and rods are made to intersect one another according to a predetermined plan so that by their proper co-operation with one another they may select any particular partial product that may occur within the limits of the machine.

The "rate strips" and "item rods" are further associated with flexible or other members connected to or formed with the shelves h of the counters and the various members are so positioned that co-ordination of two or more sets of members resulting in the same partial product will operate the same shelf, as, for example, the rate strips 3, 4 or 6 when co-ordinated with the item rods 4, 3 or 2 and vice versa will all actuate the shelf giving the partial.

According to one convenient arrangement as suggested in Fig. 7, the item rods may be fitted with cranks l or other means and the rate strips may be furnished with arms m or other members adapted to co-operate therewith so that when both the rate strip is pulled to the position shown in Fig. 7 and the item rod to be co-ordinated therewith is turned the crank l will engage and bend the arm m and the projection m' on the particular shelf strip corresponding with the partial resulting from such co-ordination will be operated. It is, however, evident that while I may thus arrange for my co-ordinator to be wholly mechanical it may also be electromagnetically or otherwise actuated and for the purpose of controlling the co-ordinator I combine with my machine any suitable type of keyboard mechanism so that the actuation of the item and rate keys (say, for example, during the typing of the particular calculation of which the result is required) will result in the selection of the particular partial prod-

ucts occurring in the specific calculation, which partial products will be delivered to their respective counters so that the result of the calculation will ultimately be indicated thereon and if necessary or desirable any suitable means may be provided for printing such result.

Referring in detail to Figs. 5 and 6, the number keys (preferably of a typewriter) are illustrated at 1, 2, 3, 4, 5, 6, 7, 8, and 9, and are so arranged as to make an electrical contact when depressed, while the keys R I are also provided for the purpose of discriminating (when a particular number key is depressed) between the operation of

the item rods and rate strips, the positive and negative terminals of the electric circuit being indicated by the signs + and -.

Each item rod i is associated with an electromagnet relay i' , i^2 , i^3 etc. (which may, for example, be of the form described in the specification of U. S. Patent No. 1,487,702 of March 25, 1924), such relays being arranged to rotate the item rods in

the manner indicated by the small arrows shown near the foot of such rods. Similarly each rate strip k is provided with an electromagnetic relay k' , k^2 , k^3 etc. which may be of a similar form but is adapted to pull the rate strips in the direction of the arrows shown near the ends thereof.

The arrangement is such that if the rate stud R is depressed the negative pole is connected with all the electromagnetic relays k' , k^2 etc. operating the rate strips, and if

now a particular key (3) is depressed a current will flow and cause the electromagnet k^3 to operate the corresponding rate strip. Similarly when the item stud I is depressed the negative pole is connected to the relays i' , i^2 etc. operating the item rods, and if

any particular number key (say 4) be now depressed the relay i^2 will be actuated to turn the item rod 4. Consequently the rate strip 3 and the item rod 4 will co-operate to move the shelf h^{12} which is so disposed

in relation to the ball tube c as to cut off 12 balls above the lower stop or shelf g so that when the latter is withdrawn from the tube simultaneously with the entry thereinto of the shelf h^{12} will also be actuated when the item 3 and rate 4 are co-ordinated and also when the item 2 and rate 6 or rate 2 and item 6 are co-ordinated.

One arrangement for simultaneously withdrawing the stop g from the tube c when any shelf is made to enter thereinto is clearly shown in Figs. 5 and 6 in which x is a member having a pin x' co-operating with a pin g' upon the stop g and a plurality of pins x^2 co-operating with similar projections upon the strips or shelves h . It will at once be seen that if any shelf h be moved in the direction of the upper arrow shown in Fig. 6, the stop g will in

consequence be automatically moved in the direction of the lower arrow.

A further very important, though not essential, feature of my invention in connection with the counting mechanism is that I arrange to count the partial products in the reverse order to that usually adopted, that is to say, the partial products first counted will be those of the highest denomination proceeding in succession to those of lower denominations, this being of importance, for example, in connection with those calculations where any figures occurring after a certain number of figures after the decimal point may be regarded as negligible.

It will be understood that the invention is not to be confined to the foregoing details of construction which are hereinbefore given by way of illustration and not of limitation, since it will be obvious that I may vary the construction and arrangement of my improved machine, the form and number of points in the counters employed, the means adopted for actuating the counting devices and co-ordinating system, and the order in which the various operations are performed—all as may be determined by the kind of calculation which the machine is required to perform, the units adopted in such calculations, the question as to whether or not printing means are to be used in connection with the machine and, in general, any particular practical requirements which the invention may be called on to fulfil.

Claims:

1. A calculating machine of the kind referred to, comprising a plurality of counting mechanisms corresponding to the various denominations occurring in the maximum result obtainable in the machine, each of which is associated with means whereby the counter may have delivered to it for counting a number of members representing any of the partial products corresponding to its denomination that may occur in any calculation within the limits of the machine.

2. A calculating machine of the character described comprising a plurality of counting mechanisms corresponding to the various denominations occurring in the maximum result obtainable in the machine, means associated with each counting mechanism whereby the latter may have delivered to it for counting a number of members representing any of the partial products corresponding to its denomination that may occur in any calculation within the limits of the machine, and means actuated by the first mentioned means adapted to free the number of members representing a partial product for delivery to the particular counting mechanism concerned.

3. A calculating machine as claimed in claim 1, in which the means co-ordinating

any particular partial products required also actuates the means by which the balls or other separate objects representing such partial products are freed for delivery to the particular counting mechanism concerned.

4. A calculating machine as claimed in claim 2, in which a single member for releasing a given partial product to the counter is actuated when any integers corresponding to that partial product are selectively co-ordinated.

5. A calculating machine according to claim 2 in which a single member for selecting a given partial product for release to a counter is actuated when any integers corresponding to the factors of that partial product are selectively co-ordinated substantially as described.

6. A calculating machine of the kind referred to comprising a counter, a storage receptacle for containing separate objects to be delivered to said counter for operating the same, a stop for holding up said separate objects, a second stop adapted to be inserted into said receptacle for holding up all the objects above said stop, and means operated by the co-ordination of two numbers for simultaneously inserting the last mentioned stop and withdrawing said first mentioned stop for releasing to the counter a number of objects corresponding to the value of the partial product of the two numbers co-ordinated substantially as described.

7. A calculating machine of the kind referred to comprising a counter, a storage receptacle containing separate objects to be delivered to said counter for operating the same, a stop for holding up said separate objects, a plurality of stops adapted to be inserted into said receptacle for holding up all the objects above said stops and means for simultaneously inserting any one of said last mentioned stops and withdrawing said first mentioned stop for permitting the delivery of a determined number of objects to said counter substantially as described.

8. A calculating machine of the kind referred to comprising a counter, a storage receptacle containing separate objects to be delivered to said counter for operating the same, a stop for holding up said separate objects, a plurality of stops adapted to be inserted into said receptacle for holding up the objects above said stops and means operated by the co-ordination of two members for simultaneously inserting one of said last mentioned stops and withdrawing said first mentioned stop for releasing to the counters a number of objects corresponding to the value of the partial product of the two numbers, co-ordinated substantially as described.

9. In a calculating machine, a plurality of members representing the product of

the multiplication of various numbers, and a plurality of groups of members, the members of each group representing numbers to be multiplied and the members of the respective groups intersecting one another at points adjacent to the first mentioned members representing the product of the multiplication of the members of the respective groups.

10 10. A calculating machine as claimed in claim 9 characterized by the provision of means located at the intersection of the respective members of the several groups for effecting movement of the first mentioned members.

11. A calculating machine as claimed in claim 9 characterized in that the first mentioned members are arranged side by side and that the members of the respective 20 groups are arranged in angular relation to one another and to the first mentioned members.

12. In a calculating machine, a plurality of members representing the product of

the multiplication of various numbers, a 25 group of parallel members representing members to be multiplied, a second group of members also representing numbers to be multiplied, the members of the second mentioned group being arranged in such 30 angular relation to the members of the first mentioned group as to intersect the latter at points adjacent to the first mentioned members representing the correct product of the multiplication of the numbers represented by the intersecting members of the first and second mentioned groups.

13. A calculating machine as claimed in claim 12, characterized by the provision of means located at the points of intersection 40 of the members of the first and second mentioned groups for engaging and actuating the first mentioned members located adjacent said points of intersection.

In testimony whereof I have signed my 45 name to this specification.

JAMES MARK McGINNIS BARR.
